UNITED STATES PATENT OFFICE.

CHARLES EDWIN SHEARON, OF HATTIESBURG, MISSISSIPPI, ASSIGNOR OF FORTY-NINE ONE-HUNDREDTHS TO ROBERT L. ANDERSON, OF HATTIESBURG, MISSISSIPPI.

RAILROAD-CROSSING GUARD.

Application filed December 5, 1923, Serial No. 678,704. Renewed March 29, 1926.

To all whom it may concern:

Be it known that I, CHARLES E. SHEARON, a citizen of the United States, residing at Hattiesburg, in the county of Forrest and 5 State of Mississippi, have invented a new and useful Railroad-Crossing Guard, of which the following is a specification.

This invention aims to provide a simple means whereby a gate or crossing guard may 10 be operated by wheels of a passing train.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described 20 and claimed, it being understood that, within the scope of what is claimed, changes in the precise embodiment of the invention shown, can be made, without departing from the spirit of the invention.

25 In the drawings:—

Figure 1 shows in top plan, a device constructed in accordance with the invention; Figure 2 is an elevation wherein parts appear in section; Figure 3 is a section on the line 3—3 of Figure 1, remote parts being omitted; Figure 4 is a section on the line 4—4 of Figure 1, remote parts being omitted.

The device hereinafter described comprises a support 1 whereon a gate 2 is pivoted at 3 for vertical swinging movement, the gate being adapted to cooperate with a striking post 4, the gate carrying depending cords 5. The gate 2 may be located at any desired height and may be of any desired construction. It may be desired to locate the gate 2 at such a height that an automobile may drive under the gate, the cords 5 striking the front of the automobile 40 to advise the driver of the vehicle that he is approaching a railroad track. The gate 2 is weighted as at 7, in order to open it.

The gate is closed by a flexible element 7 connected to the gate inwardly of the pivotal mounting 3 of the gate, the flexible element being extended downwardly about an idler 8 on the support and thence being extended horizontally, the flexible element wound about a rotary member or wheel 9 or 50 journaled at 10 on one of the ties 11 which

support the rails 12 and 14 of a track. A pitman 15 is pivoted at 16 to the wheel 9 and is pivoted at 17 to the rod 18 of a piston 19 operating in a cylinder 20, the cylinder 20 being denominated a primary cylinder. The cylinder 20 has a bleed valve 21 located behind the piston 19. A compression spring 22 is located in the cylinder 20, one end of the spring abutting against the head of the cylinder and the other end of 60 the spring abutting against the piston 19.

By means of a branch pipe 23, the rear end of the cylinder 19 is placed in communication with a main pipe 24 communicating with a storage tank 25 carrying 70 a pop valve 26, a pipe 27 leading from the tank 25 to a secondary cylinder 28 the pipe 27 being provided with a check valve 29 which opens toward the storage tank 25. A piston 30 operates in the cylinder 28 and 75 includes a rod 31 pivoted to one end of a lever 32, the lever 32 being fulcrumed intermediate its ends, as at 33 on one of the ties 11.

A base plate 34 is secured to certain of 80 the ties 11, inwardly of the rail 12 and closely adjacent thereto, the base plate carrying a stop 35. The numeral 36 marks a lever including a short curved part 37 and a longer straight part 38, the parts 37 and 85 38 being pivotally connected as at 39, the long part 38 of the lever having a curved end 40, the end 40 and the short part 37 of the lever bending away from the rail 12 at an angle thereto. The short part 37 of 90 the lever is pivotally mounted at 41 on the base plate 34, a fulcrum of the lever thus being afforded. The connection 42 is mounted slidably in the rail 12, one end of the connection being pivoted at 43 to the straight 95 part 38 of the lever 36, the other end of the connection being pivoted at 44 to the lever 32. A carrier 45, preferably in the form of a rod, is slidable longitudinally 100 in the rail 12 and the opening in the rail 12, which receives the carrier or rod 45, is of such size that the carrier, if desired, have a slight movement longitudinally of the rail 12. The same observation holds true with respect to the opening in the part 38 of 105 the lever 36, through which the rod 45 passes. Adjusting nuts 46 are threaded on the ends of the rod 45. A compression spring 47 is carried by the rod 45 and is interposed between one adjusting nut 46 110

and the part 38 of the lever 36. A similar compression spring 48 is interposed between the other adjusting nut 46 and the rail 12. The springs 47 and 48 hold the parts 37 and 38 on the lever 36 in abutment with the rail 12, as shown in Figure 3, but at the point where the body portion of the straight part 38 of the lever 36 merges into the curved part 40 of the lever, there is a space between the lever and the rail 12, as shown in Figure 4, this space being wide enough to admit the flange of a car wheel.

In practical operation, assuming that a train is proceeding along the track in the direction of the arrow A in Figure 1, the flanges of the wheels of the cars strike the curved end 40 of the part 38 of the lever 36 and impart swinging movement to the lever, the lever swinging clear of the stop 35. When, however, the train is proceeding along the track in the direction of the arrow B in Figure 1, the wheels of the cars strike the part 37 of the lever, and the lever is elongated, part 40 of the lever coming in contact with the stop 35, the stop serving to hold constant the space which exists, as shown in Figure 4, between one end of the part 38 of the lever 36 and the rail 12. The result is that the lever 36 will be swung when it is engaged by the wheels of the train moving along the track in the direction of the arrow A, whereas the wheels of a train proceeding in the direction of the arrow B in Figure 1 will not impart any movement to the lever 36 which will result in a movement of the connection 42.

When a train proceeding in the direction of the arrow A, operates the lever 36 and the connection 42, as aforesaid, the connection imparts swinging movement to the lever 32 and the piston 33 is operated, air passing the check valve 29 and being stored in the tank 25. When a sufficient pressure has built up in the tank 25, this pressure overcomes the force of the spring 22 in the cylinder 20 and the piston 19 is advanced, rotation being imparted to the wheel 9 through the instrumentality of the piston rod 18 and the pitman 15, the flexible element 7 being wound upon the wheel 10. The flexible element 7, moving over the idler 8, closes the gate barrier 2. After a sufficient period of time has elapsed, the air will leak out of the cylinder 12 through the bleed valve 21, the spring 22 reacting on the piston 19, to

move the piston 19 to the right in Figure 1, the flexible element 7 being paid off the wheel 9, and the weight 6 serving to open the gate. It will be understood that the pipe 24 is extended, so that it may be connected to a mechanism like that hereinbefore described, but located on the opposite side of the highway crossing, thereby enabling the gate to be closed regardless of the direction in which the train is proceeding. 65

What I claim is:—

1. In a device of the class described, a track rail, a lever and a fulcrum therefor, the lever comprising parts which diverge from the track rail, a stop, means for pivotally connecting said parts of the lever whereby the lever will elongate and cause one of said parts to cooperate with the stop when the other of said parts is engaged by a passing car moving in one direction on the rail, and gate operating means assembled with the first specified part of the lever and actuated thereby, through the instrumentality of a car moving in an opposite direction on the rail. 80

2. In a device of the class described, a gate, means for opening the gate; and means for closing the gate, said means comprising the rotary member, a flexible element wound about the rotary member and connected to the gate, a cylinder, a piston operating in the cylinder, means for connecting the piston to the rotary member, spring means for moving the piston in one direction, mechanism for supplying pressure to the cylinder to operate the piston in an opposite direction, and means operated by a passing car for operating said mechanism. 85

3. In a device of the class described, a cylinder, a storage tank whereinto the cylinder discharges, a piston operating in the cylinder, means actuated by a passing car for operating the piston, second cylinder in communication with the tank, a second piston operating in the second cylinder, pressure in the tank constituting means for moving the second piston in one direction, spring means for moving the second piston in an opposite direction, a gate, and means for connecting the second piston with the gate. 100 105

In testimony that I claim the foregoing as my own, I have hereto affixed my signature.

CHARLES EDWIN SHEARON.
